UNITED STATES PATENT OFFICE.

ISAAC M. SHARP, OF SAN FRANCISCO, CALIFORNIA.

OIL BURNER.

Application filed August 1, 1921. Serial No. 488,968.

To all whom it may concern:

Be it known that I, ISAAC M. SHARP, a citizen of the United States, residing at the city and county of San Francisco and State of California, have invented certain new and useful Improvements in Oil Burners, of which the following is a specification.

The present invention relates to an improvement in oil burners, particularly that type employing a horizontal rotary distributing cup and an air pressure means enabling the supplying to a fire box of a finely divided oil spray for intermixture with the required air for combustion.

One of the objects of the present invention is to provide a burner tip and cup construction capable of a double movement when inserted into or removed from a fire box opening, whereby the arc of the swing of the tip and cup is materially reduced over other devices operating in this manner. A further object is to provide a superheater for the oil in the form of a closure plate for the furnace wall opening, whereby the oil is superheated while passing through said closure plate and prior to discharging into the cup. Another object is the providing of a horizontal fulcrum for the burner formed as part of the upper half of the blower casing, providing an integral rigid structure affording a secure mount for the burner and automatic control. Other objects are the provision of an improved base for the blower which also affords a support for the motor and for the oil pump and constitutes the lower half of the blower casing.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Fig. 1 is a view in elevation, partly in section, of the preferred embodiment of my invention, disclosing more particularly the

blower discharge affording the fulcrum for the burner.

Fig. 2 is a view in side elevation, disclosing more particularly the superheater associated with the burner and the detachable fuel feed connection between the supply and burner, permitting the withdrawal or longitudinal movement of the tip and cup within the burner.

Fig. 3 is a top plain view, partly in section, on line 3—3 of Fig. 2, disclosing more particularly the mounting for the burner cup and the air tip for providing concentric strata of air currents discharging from the tip.

Fig. 4 is a broken detail view taken on line 4—4 of Fig. 3, illustrating the automatic mechanism for cutting off the fuel supply when the burner is swung from the furnace opening.

Fig. 5 is a view in elevation of the cup operating worm or screw.

Fig. 6 is a fragmentary view in side elevation of the cup operating worm or screw.

Fig. 7 is a vertical sectional view of the automatic valve arrangement in the detachable coupling of the oil feed line taken on line 7—7 of Fig. 2.

Referring more particularly to the drawings, wherein like characters of reference designate corresponding parts, 1 indicates an elongated base or support, preferably of cast metal, transversely of which is formed the lower half section 2 of a blower casing 3, said casing being of conventional form. At one end said support 1 mounts a motor 4, and at its opposite end a suitable liquid pump 5 provided with an inlet 8 and an outlet 7. A shaft 8 extends from the motor armature and connects through a coupling 9 with a shaft 10 having geared connection within a housing 11 with the pump 5, and said shaft 10 also mounts a fan or blower 12 within the casing 3. The lower half 2 of the blower case 3 mounts and has bolted thereto, as at 13, the upper half 14 of the blower casing 3, which portion is provided with a vertical discharge pipe 15 of relatively large diameter through which the air is forced from said casing 3 by the operation of the fan 12. Air is admitted into the casing 3 at a point surrounding the shaft 10 at one side of the casing through an inlet opening 16, and into said opening project the

lateral extensions 17 extending from one edge of certain of the blades 18, which are supported at their opposite edge by the web 19.

5 It will be observed that by extending the portion 17 of all or certain of the blades 18 of the fan to the outer edge of the opening 16 that air is taken directly into the fan blades instead of being drawn over the 10 blower housing.

The upper end of the vertical discharge pipe is provided with an annular supporting shoulder 20 on which rests the lower terminal edge 21 of the vertically disposed 15 inlet for the tubular burner mounting arm 22, the opposite end of which is curved or bent at right angles, as at 23, to the body of the arm 22 and is disposed in a plane at substantially 45° from the plane of the portion 20 21.

Threaded as at 24 to the end 23 of the arm 22 is a tubular coupling or member 25 integral with the outer end of which is formed a radially extending channeled casting 26 the relatively flat front wall 27 of which is adapted to contact with and provide a closure for the outer end of the opening 28 in the fire box wall 29.

The fuel oil for burning within the fire 30 box is fed to the preheating chamber 30 of the member 26 in the following manner.

From the outlet pipe 7 of the pump 5 extends a vertical pipe 31 disposed in parallel relation with the blower outlet 15, and the 35 same carries adjacent said flange 20 a valve casing 32 within which is mounted a conventional valve having a stem 33, the valve casing being secured to a boss 34 at the upper end of the pipe 15. Upwardly from the 40 valve casing 32 extends a pipe 35 connected through an elbow 36 with a short pipe section 37' threaded into a casting 37 formed with a vertical opening adapted to align under certain conditions with an opening 38 45 formed in a plug 39 which is threaded into a recess in the top wall of the arm 22, as in Fig. 4.

A bolt 40 extends through an opening in the member 37 and threads into the member 39, providing with said flange 20 and portion 21 a fulcrum for the upper and lower surfaces of said arm 22 enabling the same to be readily swung on a vertical axis without liability of the same becoming detached from its support.

The opening 38 in the plug 39 communicates with one end of a longitudinally disposed channel 41 in the upper surface of the arm 22 and into the discharge end of 60 said channel is threaded a fitting 42.

The fitting is of the double channeled type and with the channel 43 affording an outlet for the oil in channel 41 is connected a pipe 44 communicating with the chamber 30 at 65 a point below the chamber dividing wall 45

and from another portion of said chamber extends a pipe 46 connecting with the outlet or discharge channel 47 of the fitting 43, as illustrated in Figs. 2 and 7 of the drawings.

70 The discharge of the oil from the channel 47 is controlled by a valve 48 normally forced by a spring 49 to rest on a seat 50, and the stem 51 of said valve is at its outer end provided with a releasing pin 52 for the 75 hereinafter described purpose.

Longitudinally movable within the tubular coupling or member 25 and within the portion 23 of the arm 22 is the inner end 80 of a tubular burner tip 53 carried by the peripheral surface 54 of a hub 55 which mounts the surface 54 on webs or spiders 56 radially extending therefrom.

Forwardly from the hub 55 extends a tubular cup supporting spindle 56, which rotatably mounts on bearings 57 held in place by a nut 58, a screw casing or hub 59, which carries on its periphery a spirally extended 90 radially disposed worm or screw 60 formed in its rear face with the grooves or depressions 51 disposed radially to the axis of rotation of said hub 59.

Threaded to the outer end of the hub 59 is a burner cup 62 of the well known construction, and into the inner end of which 95 discharges the oil flowing through the tubular spindle 56. The cup at its outer end is provided with an annular curved lip 63 which projects beyond the end 64 of a detachable end ring or portion 65 which surrounds the end of the cup 62 and is threaded as at 66 to the end of member 53.

100 The outer end of said ring 65 is annularly grooved as at 67 and said groove connects with the interior of the member 53 at a point near the free end of the cup 62 through a plurality of air passages 69, this construction being particularly illustrated in Fig. 3 of the drawings.

Air under pressure, forced by the blower 110 into the member 25, strikes against the spiral or worm 60 and is thrown therefrom in a complete whirling volume, driving the cup in an opposite direction, thereby increasing the atomizing force of the air as it leaves the space A between the inner surface of the ring 64 and the outer end of the cup 62 immediately within the bell portion 63 thereof. This contracted portion A causes a high velocity to be imparted to the air 115 and causes a slight creation of pressure within the member 53 surrounding the cup 62, a portion of which passes through the apertures 68 and discharges from the annular groove 67 in the ring 64, thereby affording with the whirling volume passing through the opening A two distinct concentric volumes of air, the outer one converging into the inner one at a point removed from the end of the cup 62, and 120 125 130

which air volumes pick up the radially thrown oil film as it leaves the bell 63 and direct the same, completely atomized, in a direction outwardly from the member 53.

- 5 To enable the telescoping or inward movement of the member 53 within the members 23 and 25, when it is desired to swing the burner from the opening 28, and to further provide a controllable oil feed for the tubular spindle 56, I thread to the rear of the hub 55 a pipe 69 longitudinally movable in a tubular guide 70 within the arm 22, and said pipe extends through a threaded boss 71 and carries an annular bevelled flange 72 for contacting with the wall of the boss and detachably secured thereto by a suitable nut 73 having an accentuated pitch connection 74 with the boss 71, and said nut carries a handle grip portion 75; this enabling the ready detaching and connection of the nut on the boss 71.

Threaded to the extreme end of the pipe 69 is a tubular fitting 76 of the elbow type, mounting at its lower end a needle valve 77 for controlling the opening at the outer end of the pipe 69, and the upper end of said elbow fitting is formed with a conical recess 78 for overlying the conical end of the outlet channel 47, as in Fig. 7, and providing a friction joint between the two members. The upper end of the fitting 76 is normally closed by a spring pressed valve 79, the stem 80 of which is provided with an extension 81, adapted on the connection 35 of the members 43 and 76 to contact with the portion 52 of valve 48 and affording a through passage from the pipe 46 into the pipe 69 for the preheated oil prior to discharging into the cup 62.

40 The release of the nut 74 to telescope the member 53 within the members 23 and 25, will permit of the breaking of the connection at the upper end of member 76, and the valves 48 and 79 will be automatically seated, thereby preventing any flow of fuel through said broken connection, and the vertical portion of said fitting 76 will afford a handle for moving the member 53 within said members 25 and 23.

50 Within the outlet 15, if desirable, may be mounted a damper 82, and with the stem 83 of which is connected within its length a lever 84 attached at one end through a chain 85 with a draft damper or door 86 associated with the fire box. The opposite end of the lever connects through a link 87 with a second lever 88 secured to the valve stem 33 and operating between adjustable stops 89. The opposite end of the lever 88 connects through a member 90 with a suitable stem operated device associated with the fire box boiler, whereby on the steam within the boiler attaining a given pressure, the various levers are operated to 65 reduce the flow of oil; reduce the flow of

air and reduce the draft controlled by the door 86.

Having thus described my invention, what I claim as new and desire to secure by Letters Patent of the United States 70 is:-

1. An oil burner, consisting of a blower casing provided with a vertically disposed discharge pipe, a tubular burner supporting arm providing an air passage disposed laterally therefrom and at one end resting on said pipe and adapted to swing thereon on a vertical axis, a burner associated with the other end of said arm and extending at substantially right angles thereto, 75 means for forcing air through said blower casing to said burner, and means for supplying oil to the burner.

2. An oil burner, consisting of a blower casing provided with a vertically disposed discharge pipe, a tubular burner supporting arm, providing an air passage disposed laterally therefrom and at one end resting on and supported by said pipe to swing thereon on a vertical axis, a burner extending 90 at substantially right angles from the other end of said arm and capable of telescopic movement within the same, means for forcing air through said blower casing to said burner, and means for supplying oil 95 to the burner.

3. In combination with a fire box opening, a burner supporting arm fulcrumed at one end to permit its free end to swing in an arcuate path into registering alignment with the fire box opening, a burner including a burner tip and rotary cup mounted for operative telescopic movement within the free end of the arm, said burner adapted for operative extension to project 105 from the free end of the arm into the fire box opening and preclude movement of the arm from registry therewith.

4. In combination with a fire box opening, a burner supporting arm formed at 110 one end with an angularly bent portion and fulcrumed at its opposite end adjacent to said opening to permit its free end to swing in an arcuate path into registering alignment with the fire box opening, a burner 115 within the bent portion and longitudinally movable therein, said burner including a rotating cup and a burner tip, and means for telescopically moving the burner relatively to the free end of the bent portion 120 of the arm, said burner when extended precluding the swinging movement of the arm from registering alignment with the fire box opening.

5. An oil burner, comprising a tubular 125 burner supporting arm affording an air supply pipe mounted at one end to swing on a vertical axis, a shell projecting horizontally from the opposite end thereof at right angles thereto, a cup rotatably mount- 130

- 4
- d within the shell, said cup and shell adapted for simultaneous telescopic movement within said arm, means for supplying oil to the cup, and means for supplying air to said pipe to cause the rotation of the cup and to intermix with the oil discharging therefrom.
6. An oil burner, comprising a tubular burner supporting arm affording an air supply pipe mounted at one end to swing on a vertical axis, a burner shell projecting from the opposite end thereof and adapted for telescopic movement therein, a cup rotatably mounted within the shell, a spindle supporting the cup, an oil feed pipe for supplying oil to the cup through the spindle and extended exteriorly of said air supply pipe, said oil feed pipe affording a means for imparting simultaneous telescoping movement of said shell and cup as a unit within said arm, means for supplying oil to said pipe, and means for supplying air to said air supply pipe
7. An oil burner, comprising a burner shell, a cup rotatably mounted therein with its wall in slight spaced relation to the burner shell wall providing a primary annular air escape therebetween, an air actuated impeller associated with the cup, means for supplying air under pressure into the shell for actuating said impeller, means for supplying oil to the interior of said cup, and a ring carried by the outer end of said shell and formed with an annular air escape channel opening through its end wall, said ring provided with a plurality of openings for permitting the passage of air from the space between said shell and cup into said annular air escape channel.
8. An oil burner, comprising a hollow shell, a cup rotatably mounted therein with its end terminating approximately at the end of said shell, means for supplying air under pressure to said shell for rotating said cup therein, means for supplying oil to the cup, and a ring secured to the end of said shell and provided in its outer end wall with an annular channel, said ring being provided with a plurality of air inlet openings connecting the inner end of said channel with the interior of said shell whereby a portion of the air supplied to said shell is caused to issue through said annular channel, the walls of said shell and the walls of said channel being so disposed as to direct the air stream issuing therefrom to intersect the axis of rotation of the cup at a point removed from in front of said burner.
9. An oil burner, comprising a burner tip for projecting through a fire-box wall opening, means for feeding air and oil under pressure to the burner to discharge from said tip into the fire-box through said wall opening, and a heating chamber through which the oil passes prior to discharging from said tip, said chamber extending radially from the burner and the wall affording a closure for said wall opening and adapted to be heated by the reflex heat from said fire-box.
10. An oil burner, comprising a tubular burner supporting arm mounted at one end to swing on a vertical axis, a burner extended horizontally at right angles from the other end of said tubular arm and adapted for arcuate swinging movement for positioning within and removal from a fire-box wall opening, a heating chamber disposed radially of said supporting arm and through which oil supplied to said burner passes prior to discharging therefrom, the wall of said chamber affording a closure for said fire-box wall opening and adapted to be heated by the reflex heat from said fire-box, and means for supplying air and oil under pressure to said burner.
11. An oil burner, comprising a tubular burner supporting arm mounted at one end to swing on a vertical axis, a burner extended horizontally at right angles from the other end of said tubular arm, and adapted for arcuate swinging movement with said arm for positioning within and removal from a fire-box wall opening, a heating chamber cast integral with said arm and extended radially therefrom in a plane at right angles from the line of passage of the burner, said heating chamber wall adapted to close the fire-box wall opening and to be heated by the reflex heat from said fire-box, and means for feeding air and oil to said burner.
12. In combination with a liquid fuel burner, a tubular support therefor and longitudinally within which said burner is adapted for telescopic movement, said support affording an air supply for the burner, a pipe extending through the tubular support and affording the air supply for the burner, a detachable coupling within said pipe adapted for separation to permit the longitudinal telescopic movement of said burner within said support, a valve in said pipe at one side of said coupling and adapted for closing on the separating of said coupling, whereby the discharge of oil from said pipe is cut off, and means for feeding air and oil to the burner.
13. In combination with a liquid fuel burner, a tubular support therefor and longitudinally within which said burner is adapted for telescopic movement, said support affording an air supply for the burner, a pipe extending through the tubular support and affording an air supply for the burner, a detachable coupling within said pipe adapted for separation to permit the longitudinal telescoping movement of said burner within said support, and a pair of valves in said pipe one at each side of said coupling and adapted for automatically clos-

ing on the separating of said coupling whereby the discharge of oil from opposite sides of said coupling is precluded, and means for feeding air and oil to the burner.

- 5 14. In combination with a liquid fuel burner, a tubular support therefor and longitudinally within which said burner is adapted for telescopic movement, said support affording an air supply for the burner, a pipe 10 extending through the tubular support and affording the air supply for the burner, a detachable coupling within said pipe adapted for separation to permit the longitudinal telescopic movement of said burner within 15 said support, an automatic valve in said pipe at one side of said coupling, said valve being normally unseated during the attachment of said coupling, and for automatically seating on the separating of said coupling to shut off 20 the discharge of oil therefrom, and means for supplying air and oil to the burner.

- 15 15. In combination, a base, an oil pump supported at one end thereof, a motor at the other end thereof, a blower casing positioned between said motor and pump and consisting of upper and lower sections, the lower section being cast integral with said base and said upper section resting on said lower section and provided with a vertically disposed discharge pipe extended therefrom, an oil burner, a tubular supporting arm therefor extending laterally therefrom and co-operating at its opposite end with said discharge pipe whereby 30 said support and a vertical fulcrum are provided for said arm, an oil pipe extending parallel with said casing discharge pipe, an oil conducting channel within said arm leading to said burner, a coupling connection 35 between said pipe and channel in alignment with the axis of fulcrum of said arm, said coupling provided with passages adapted for movement out of register to interrupt the oil flow into said channel on 40 the swinging of said arm to a predetermined position, and a blower in said casing.

- 45 16. In combination with a tubular burner shell, an elongated cylinder mounted therein, bearings supporting said cylinder 50 at its opposite ends, an impeller vane extending from the periphery of said cylinder and disposed spirally about the same between said bearings, a cup carried by the end of the cylinder and rotatable therewith, 55 means for supplying air to said shell for rotating said cylinder and cup, and means for supplying oil to the cup.

- 60 17. In combination with a tubular burner shell, an elongated cylinder rotatably mounted therein, an impeller vane extending 65 from the periphery of said cylinder and disposed spirally about the same, said vane provided in one face with a plurality of air pockets disposed radially of 70 the axis of rotation of the end of the cyl-

inder, a cup carried by the cylinder and rotatable therewith, means for supplying air to said shell for rotating said cylinder and cup, and means for supplying oil to the cup.

70

18. In combination with a tubular burner shell, a spider disposed transversely thereof, a tubular spindle extending therefrom forming a hub and disposed longitudinally within the shell, an elongated cylinder rotatable on said hub and provided on its periphery surrounding the hub with a spiral impeller vane, a cup supported by and detachably secured to the outer end of the cylinder and terminating at the outer end of the shell, bearings rotatably supporting said shell at its opposite ends on said spindle, and means for supplying air to the shell and oil to said spindle for discharging into said cup.

75

19. In combination with a tubular burner shell, a tubular spindle disposed longitudinally within the same, means for supplying air to the shell and oil to the spindle, a cup supporting and rotating cylinder rotatably mounted on said spindle, a plurality of supporting bearings within said cylinder and carried by said spindle, a cup in the outer end of said shell and threaded into the outer end of said cylinder, and an impeller vane carried by the periphery of the cylinder and extending spirally around the same for substantially its full length with its outer edge disposed in slight spaced relation to the inner surface of the shell.

80

20. An oil burner including a tubular air pipe, an oil cup rotatably mounted in the discharge end thereof and actuated by the air pressure within said pipe, an oil supply pipe discharging into said oil cup, a valve in said air pipe, a valve in said oil pipe, and a connection between said valves whereby the same are simultaneously operated to proportionately increase or decrease the respective fluid flows therethrough.

85

21. An oil burner including a furnace provided with a burner receiving opening and a damper controlled draft opening, an oil burner discharging into the burner receiving opening and including a valve controlled air supply pipe, an oil cup rotatably mounted in the discharge end thereof and actuated by the air pressure in said pipe, a valve controlled oil supply pipe discharging into said cup, and a connection between the valves in said pipes and said draft damper whereby the three elements are adapted to be simultaneously operated to correspondingly vary the fluid passing through the openings controlled thereby.

90

22. An oil burner including a furnace provided with a burner receiving opening and a damper controlled draft opening, an

100

oil burner discharging into the burner receiving opening and including an air supply pipe, an oil cup rotatably mounted in the discharge end thereof and actuated by the air pressure in said pipe, a valve controlled oil supply pipe discharging into said cup, and a connection between the valves in said oil pipe and said draft damper

whereby the two elements are adapted to be simultaneously operated to correspondingly vary the fluid passing through the openings controlled thereby.

In testimony whereof I have signed my name to this specification.

ISAAC M. SHARP.
